AIR COOLING MEANS

James J. Yoch, St. Louis, Mo.

Application September 25, 1935, Serial No. 42,042

5 Claims. (Cl. 257—70)

This invention relates to cooling apparatus and more particularly to that type of cooling apparatus which is adapted to cool either air or water, and with it or them other fluids approximately to the wet bulb reading of the atmosphere.

One of the particular uses of the invention is to cool a condenser coil for a refrigerating system, and at the same time provide cooling for water used as a heat exchange agent in a jacket above the cylinder of a refrigerant compressor. One of the virtues of this invention is that water used for cooling is constantly recirculated, whereas in pressure systems using tap water for cooling, the water after being used once is wasted. Thus this invention, among other advantages, saves the expense of the large volume of water required therefor.

An object of the invention, therefore, is to provide improved apparatus which is simple in construction, durable in service, efficient in operation, and economical to use, which will reduce temperatures of a fluid medium from a comparatively high temperature to approximately a wet bulb reading of the atmosphere at room conditions.

Another object of the invention is to provide a condenser for a refrigerating system with improved cooling means therefor which will be simple, efficient and economical.

Other and specific objects will be apparent from the following detail description taken in connection with the accompanying drawings, while many inherent advantages of the invention will also be apparent from the description.

Fig. 1 is a side elevation of an enclosed structure embodying the invention;

Fig. 2 is a horizontal section on line 2—2, Fig. 1;

Fig. 3 is a vertical section on line 3—3, Fig. 2;

Fig. 4 is a vertical section on line 4—4, Fig. 3;

Fig. 5 is a fragmentary section on an enlarged scale showing the addition of a water pump;

Fig. 6 is a sectional view of an alternate type of device; and

Fig. 7 is a sectional view on line 7—7, Fig. 6.

The drawings show the invention embodied in a device particularly suitable for use as a condenser in a refrigerating system, with means for cooling and recirculated water in a circuit to the cylinder head of a compressor in the same refrigerating system.

The apparatus as specifically illustrated in the drawings, Figs. 1 to 5, comprises a housing 1 having an air intake 2 near one end 3 of a cover 4, and an air outlet 5 at or near the opposite

end 6 of the cover 4. The lower portion of the housing provides a tank 7 adapted for holding a body of water, the maximum level of the water being indicated by the numeral 8.

Water may be supplied to the tank 7 by any convenient means. As specifically shown, it is supplied through a pipe controlled by a manually operable valve 9 and the water may be drained from the tank through a nipple 10, which is normally closed by a removable cap 11. 10 A float 12 is adapted to automatically maintain a constant and proper water level. A blower 13 fixed on a shaft 14 is suspended substantially above the water line 8. A motor 15, shown as directly connected to the blower 13 by the shaft 15 14, is secured by bolts 16 to a bracket 17, which in turn is rigidly secured to a housing 18 for the blower 13 by bolts 19.

A star shaped continuous vertical baffle plate 20 is attached to the underside 21 of the blower 20 housing 18. The baffle 20 is so shaped, positioned and arranged as to permit water to be drawn from the tank 7 into the blower, where it is mixed with air without, however, materially affecting the amount of air taken in by the blower. 25 The bottom edge of the baffle 20 is above the water level. When the blower is in operation the baffle confines a section of the air stream thereby producing an effective suction upon the surface of the water. At the same time the turbulence 30 of the air stream causes the water to splash, in which condition it is more readily taken up by the air stream. By the arrangement described, a substantial quantity of water is lifted with the air stream into the blower, where it is intimately 35 mixed with the air. By making the baffle 20 star shaped, the necessary turbulence of the air stream is obtained to splash the water and an additional advantage is obtained. By using an irregular shaped device a greater opening for 40 admission of air is obtained as compared with a circular baffle. This is important because the lower edge of the baffle must be close to the water, and the additional opening afforded by the use of an irregular shape adds materially to the 45 efficiency of the device.

The intake end 22, of the tube 23 carrying the refrigerant fluid to the condenser coils enters the housing 1 through an opening 24, and connects with a header 25. The header 25 joins the top row 50 26 of coils 27, thereby separating the refrigerant fluid into a number of streams carried by the coils 27. The bottom row 28, of the first series of coils 27, are joined together by another header 29, and the refrigerant fluid emerges in one 55

stream through the tube 30, which tube 30 continues to a second series of coils 31. The tube 32, carrying the cooled fluid, passes through an opening 33 in the housing 1, and thence returns 5 to a refrigerating unit or evaporator (not shown in the drawings).

Fins 34, support the first series of coils 27, and also gather moisture, thereby aiding and increasing the evaporation process. The fins 34 also 10 assist in eliminating moisture from the air-water stream. The coils 31 are suspended above the floor 35 of the coil housing 36, leaving a space 37 for water to flow under the coils 31. A row of holes 38 in the floor 35 of the coil housing 36 permits 15 the water to flow back to the tank 7.

In the operation of the device, the blower 13 draws air through an intake opening in the bottom of the blower housing 18, causing a suction or partial vacuum and, assisted by the form and 20 arrangement of the baffle plate 20, draws with the air a substantial amount of water from the tank 7. The blower 13 includes a series of plates 40 which, rotating at a high rate of speed, breaks up the water into small particles and thus an air-water spray is expelled by the blower toward 25 and upon the coils 27. The tubes and coils 27 are placed in staggered relationship to each other, as plainly shown in Figs. 3 and 4 thereby serving as a series of baffle plates upon which free water 30 from the air-water mixture collects. The fins or plates 34 also collect water. The water so collected trickles down to the lower coil 31 and flows around and under the coil along the floor 35 to make an exit from the condenser housing 36 of the tank 7. It will be understood that additional corrugated fins may be placed in the air exit 5 to eliminate further moisture if desired.

The water, which is being recirculated by being drawn from the tank 7 and projected against 40 the condenser coils and then returned to the tank 7, is being cooled by evaporation to approximately the wet bulb temperature of air received through the inlet 2. This water may be used, therefore, for heat exchange purposes and in a 45 refrigerating system may be used to cool the cylinder of a compressor used in the refrigerating system. In Fig. 5 an addition is illustrated which includes a water pump 42 driven by the shaft 14 which in this case is extended downward. The 50 pump 42 is adapted to force a stream of water through a pipe 43 leading to the compressor cylinder (not shown in the drawings) and thence through another pipe 43a back to the tank 7.

An alternate type of cooler is shown in Figs. 6 55 and 7, in which a pump is employed, not only to circulate the water to the cylinder of the compressor but also to project a stream of water upon the plates of the blower. In the device specifically illustrated in these figures, air enters an 60 intake 44, flows downwardly between a coil housing 45 and an outer housing 46 and is drawn upwardly by a propeller type fan 47. A water pump 42 forces a stream of water through a pipe 48 and a smaller pipe 49, connected at 50, with 65 the pipe 48, the pipe 48 continuing outwardly through the wall of the housing 46 for connection to the cylinder jacket of a water cooled compressor, not shown in the drawings. The pipe 49 enters the coil housing 45 through a hole 51 and terminates at the nozzle 52, positioned and arranged to cause a stream of water to flow downwardly upon the fan 47. This water stream is 70 broken into a spray by the revolution of the fan 47, and an air-water spray is thus forced upwardly and around coils 53 carrying the refriger-

erant fluid. The coils 53 are connected by an inlet tube 54 which enters the outer housing 46 through a hole 55 and the coil housing 45 through a hole 56, and is adapted to conduct heated refrigerant fluid into the condenser coil 53. A 5 header 57 to which the tube 54 is directly connected divides the refrigerant fluid into separate streams, and a header 58 at the bottom joins these streams. An outlet tube 59 is connected to the header 58 and conducts the cooled refrigerant fluid outwardly through the walls of the housings 45 and 46 for use in evaporating units. The coils 53 are staggered to catch most of the free water in the air-water stream and a helical baffle 60, or other eliminator may be inserted in an air 10 outlet 61 if desired.

The fan 47 is driven by a directly connected motor 62 through a common shaft 63. The motor 62 is enclosed in a housing 64 which has an air inlet 65 and an air outlet 66. The air outlet 66 is 15 connected to the air space between the housings 45 and 46, and thus the fan 47 causes a suction at the outlet 66 to produce a current of air inwardly through the inlet 65 about the motor and outwardly at the port 66.

The housing of the device may be supported by 20 legs 123. A cord 124 with a plug 125 allows the motor to be attached to any convenient outlet for power.

While the invention has been described as embodied in a device used as a condenser for a refrigerating system and to cool water for use in the water jacket about the cylinder of an air compressor, the invention can be applied wherever it may be useful to cool air or water, or other fluids, to a temperature equivalent to the wet bulb reading of the atmosphere in which the device may be placed. It will be obvious, therefore, that various changes may be made in the details of construction within the scope of the 40 appended claims, without departing from the scope of this invention, and that parts of the invention may be used without the whole.

It is understood that the words "blower", "fan", "air", "water", etc., are intended to be broad 45 and comprehensive and to include within their scope equivalents which will service the purpose of the particular features or aspect of the invention defined by the claims.

Having thus described this invention, I hereby 50 reserve the benefit of all changes in form, arrangement, order, or use of parts, as it is evident that many minor changes may be made therein without departing from the spirit of this invention or the scope of the following claims.

I claim:

1. An apparatus of the character described, consisting of a tank adapted to hold a body of water, an air intake and an air outlet in the above-mentioned tank, a blower adapted to circulate air and water, a plurality of coils placed in the path of the circulating air and water, the said coils adapted to convey refrigerant fluids, fins adapted to suspend the above-mentioned coils, the said fins also adapted to gather part 60 of the moisture from the air-water current, a coil connected below the first-mentioned coil, whereby water will trickle from the above-mentioned fins upon said coil, and power means to revolve the above-mentioned blower.

2. In refrigerating apparatus, a housing adapted for holding water at its bottom, a centrifugal blower mounted in said housing in spaced relation above the surface of the water, a stationary baffle between the blower and the water 75

positioned so as to cause water to be entrained in an air stream induced by the blower, an air intake and an air outlet in the housing, and coils in the housing adapted for conveying refrigerating fluids and positioned in the path of the water laden air stream from the blower.

5. In refrigerating apparatus, a blower mounted in spaced relation above a body of water, and a star shaped vertical baffle mounted beneath the blower and spaced above the said surface of the water.

10. In refrigerating apparatus, a housing adapted for holding water at its bottom, means for maintaining a constant water level in the housing, a centrifugal blower mounted in said housing with its inlet in spaced relation above the water, a stationary baffle between the blower and the water positioned so as to cause water to be entrained in an air stream induced

by the blower, an air intake and an air outlet in the housing, and coils in the housing adapted for conveying a refrigerant fluid and positioned in the path of the water laden air stream from the blower.

5. In refrigerating apparatus, an outer housing adapted to hold a body of water in its bottom, an air intake in the outer housing, an inner housing having an air intake spaced above the water, condenser coils in the inner housing and 10 a blower in the inner housing adapted to draw air through the air intake of the outer housing over the body of water and through the intake of the inner housing and to project it against said coils, and a baffle between the air intake of the inner 15 housing and the body of water to increase the turbulence of the air stream and cause the water to be splashed and entrained in the air stream.

JAMES J. YOCH.
